UNITED STATES PATENT OFFICE.

WILLIAM C. F. MIELKE, OF HOWARD LAKE, MINNESOTA.

ANTISLIPPING DEVICE FOR WHEELS.

1,197,222.

Specification of Letters Patent. Patented Sept. 5, 1916.

Application filed May 15, 1916. Serial No. 87,709.

To all whom it may concern:

Be it known that I, WILLIAM C. F. MIELKE, a citizen of the United States, residing at Howard Lake, in the county of Wright, State of Minnesota, have invented certain new and useful Improvements in Anti-slipping Devices for Wheels; and I do hereby declare the following to be a full, clear, and exact description of the invention, such as will enable others skilled in the art to which it appertains to make and use the same.

This invention relates to an anti-slipping device for wheels.

15 An object of the invention resides in the provision of a device for preventing the slipping of the wheels of a vehicle, which means is rendered operative simultaneously with the application of the brakes.

20 A further object of the invention resides in so constructing the device that it will be in no way injurious to the tires of the vehicle wheels.

With these and other objects in view, such 25 as will appear as my description progresses, my invention comprises the combination and arrangement of parts as set forth in and falling within the scope of the appended claims.

30 In the drawing: Figure 1 is an elevational view of the inside of a wheel showing a device constructed in accordance with my invention mounted thereon; Fig. 2 is an elevational view looking at the edge of the 35 wheel; Fig. 3 is a vertical sectional view of a portion of the device showing the manner in which the slide is mounted; Fig. 4 is a similar view taken at right angles to Fig. 3 and showing the form of the actuating cam; Fig. 5 is a sectional view on line 40 5-5 of Fig. 3; Fig. 6 is a plan view showing the controlling means for the brake; Fig. 7 is a detail showing the manner in which the brake band is supported, and Fig. 45 8 is a sectional view showing the manner in which the controlling lever is mounted.

In the drawing I have illustrated an automobile wheel conventionally, which wheel includes a hub 1, spokes 2, a felly 3 and 50 a tire 4.

In order that the wheel may be prevented from skidding I have secured a drum 5 to the hub 1 by means of bolts 6, which drum is provided with flanges 7 and 8. A brake 55 drum 9 is provided, which drum is rotatable on the drum 5 and bears against the inner

flange 8, at 10. An annular plate 11 is provided which is secured by suitable means 12 to the flange 7 of the drum 5, which plate coöperates with the drum 9 to close 60 the drum 5. A cam wheel 13 is secured, by means of screws 14, to the drum 9 and lies within the drum 5, being held in spaced relation to the wall thereto by means of a projection 15. This cam wheel rotates on 65 the flange 8 as will be readily observed from the drawing and is provided with a plurality of cam fingers 16 with depressions 17 therebetween. An annular plate 18 is secured by means of bolts 19 to the felly 3 70 of the wheel and extends inwardly therefrom. This plate 18 is provided with a plurality of openings 20, in which openings sleeves 21 are slidably mounted. These castings are provided, at their outer ends, with 75 spurs 22 which are held therein by bolts 23. Slides 24 extend into the inner ends of the sleeves and are slideable therein, the movement being limited by the engagement of pins 25 which are secured to the slides and extend through slots 26 in the sleeves. The sleeves and slides are normally pushed apart by means of springs 27 which are located in the sleeves and interposed between the ends 80 of the slides and the inner ends of the spurs 85 22. The inner ends of the slides 24 extend through openings in the flange 7 of the drum 5 and are provided with rollers 28 which ride upon the cam fingers 16 of the cam wheel 13 as the latter is rotated with 90 respect to the drum 5.

When the device is in its normal position, that is to say, when the wheel is operating without necessitating the use of the anti-slipping device, the rollers 28 will be located in the depressions 17 in the wheel 13 and the spurs 22 will be drawn inwardly by means of coil springs 29 which are secured to the sleeves 21 as illustrated in the drawing. Now as the brake drum 9 rotates with 100 the wheel, the relative positions of the cams 16 and the rollers 28 will remain the same so that the spurs 22 will not be pushed beyond the periphery of the wheel. When, however, the brake is applied so that the drum 9 is arrested the wheel 13 will likewise be arrested and consequently as the vehicle wheel rotates the rollers 28, which move with the wheel, will ride to the points of the cams 16 so that the slides and sleeves will be forced 105 outwardly to cause the spurs 22 to penetrate the ground, the shock of the penetration 110

being absorbed by the springs 27. The skidding of the wheel will in this manner be prevented.

In order that the movement of the brake drum may be arrested, I have provided a brake band 30 which is secured to a crank portion 31 on one end of an operating rod 32. This operating rod extends between and is rotatably mounted in a bearing 33 on the rear radius rod of the vehicle. In order that this rod 32 may be rotated, I have provided the same with a crank portion 34 to which a link 35 is connected, which link is connected at its other end to a lever 36 which is adapted to be located adjacent the seat of the operator so that the application of the brakes and the anti-slipping device will be under his control. Secured to the brake band 30 is a casting 37 which is provided with a slot 38 and in which a spring 39 is located. An arm 40 is pivoted to the brake drum and has a pin which extends into the slot 38 and is normally held in the upper end thereof by the spring 39. This arm 40 maintains the brake band in spaced relation to the brake drum when the former is not in use and thus prevents any rattling.

While I have described only the mechanism as applied to one wheel it is to be understood that this is duplicated on the other wheel.

It will thus be seen that I have provided an anti-slipping device for vehicles which is so constructed that it will not interfere with the tires of the wheel of the vehicle and so that it will be applied automatically with the application of the brakes.

While I have illustrated and described a particular embodiment of my invention, it has merely been for the sake of convenience

and I do not wish to be limited to that particular embodiment as it is obvious that numerous changes may be made in the details of construction without departing from the spirit of the invention or exceeding the scope of the appended claims.

What I claim is:—

1. The combination with a vehicle wheel, of a drum mounted thereon and having a pair of spaced inwardly extending flanges, 50 an annular plate secured to the felly of the wheel in parallel relation to the flanges, a slide mounted in the annular plate and in one flange of the drum and having means on the end thereof for penetrating the ground, 55 a roller on the inner end of the slide, a cam wheel rotatably mounted within the drum and means for maintaining said cam wheel stationary so as to cause the slide to move outwardly through the flange and the afore- 60 mentioned annular plate.

2. The combination with a vehicle wheel, of an annular plate secured to the felly thereof and extending at right angles to the plane of the wheel, a sleeve slidably mounted in the plate and having a spur in the end thereof, a slide slidably mounted in the sleeve, means for limiting the sliding movement between the sleeve and slide, resilient means normally tending to force said slide 70 and sleeve apart, a brake drum and means operated by the brake drum for moving said sleeve outwardly.

In testimony whereof, I affix my signature, in the presence of two witnesses.

WILLIAM C. F. MIELKE.
